UNITED STATES PATENT OFFICE.

ALVIN A. QUANDEE AND STONE G. PALMBERG, OF CHICAGO, ILLINOIS.

DESIGN FOR A COMBINATION FORK AND SPOON.

60,369.

Specification for Design.

Patented Feb. 7, 1922.

Application filed December 22, 1920. Serial No. 432,625. Term of patent 3½ years.

To all whom it may concern:

Be it known that we, ALVIN A. QUANDEE and STONE G. PALMBERG, citizens of the United States, residing at Chicago, in the county of Cook and State of Illinois, have invented a new, original, and ornamental Design for a Combination Fork and Spoon, of which the following is a specification, reference being had to the accompanying drawing, forming part thereof.

Figure 1 is a rear elevational view; and

Figure 2 is a side elevational view of a combination fork and spoon, showing our new design.

We claim:

The ornamental design for a combination fork and spoon, as shown.

ALVIN A. QUANDEE.
STONE G. PALMBERG.
